United States Patent Office

Des. 196,793
Patented Nov. 5, 1963

196,793

LOUNGE CHAIR

Henry P. Glass, Northfield, Ill., assignor to Contour
Chair-Lounge Co., Inc., St. Louis, Mo., a corporation of Missouri

Filed May 2, 1963, Ser. No. 74,726

Term of patent 14 years

(Cl. D15—11)

Fig. 1.

Fig. 2.

Fig. 3.

Fig. 4.

Fig.5.

Fig.6.

FIGURE 5 is a perspective view thereof, showing the near arm in lowered position and the other arm in raised position; and

I claim:

The ornamental design for a lounge chair, as shown.
